UNITED STATES PATENT OFFICE.

JAMES RICHARD JONES, OF JAMESTOWN, NEW YORK, ASSIGNOR TO ART METAL CONSTRUCTION COMPANY, OF JAMESTOWN, NEW YORK, A CORPORATION OF NEW YORK.

PROGRESSIVE ROLLER SUSPENSION.

Application filed February 28, 1927. Serial No. 171,686.

The object of this invention is to provide a new and improved form of progressive roller suspension for the drawers of a metal filing cabinet. This and other objects of the invention will be illustrated in the drawings, described in the specification, and pointed out in the claims at the end thereof.

In the drawings:

Figure 1 is a side elevation of the suspension collapsed as it is assembled in the case.

Figure 2 is a side elevation of the suspension extended, the parts being the same as are shown in Figure 1, but are shown on a smaller scale.

Figure 3 is an end view of the left hand end of Figure 1.

Figure 4 is a vertical section on the line 4^x, 4^x of Fig. 1.

Figure 5 is a vertical section on the line 5^x, 5^x of Fig. 4. This figure shows the parts at the middle of Figure 1 on an enlarged scale.

Figure 6 is a vertical section on the line 6^x, 6^x of Fig. 2.

Figure 7 is a vertical section on the line 7^x, 7^x of Fig. 2.

Figure 7^A is a detail view showing the roller mounted to turn on a swinging eccentric.

Figure 7^B is a detail view showing the roller mounted to turn on a swinging link.

Figure 8 is a detail view of a portion of Fig. 2 indicated by the arrows 8^x, 8^x the upper flange of the casing channel being partly broken away to expose the parts that would otherwise be concealed thereby.

Figures 3 to 8 inclusive show the parts on twice the scale as they appear in Figure 1.

Figure 9 is a plan view of the blank from which the stationary channel on the case is formed.

Figure 10 is a plan view of the blank from which the floating member of the suspension is formed.

Figure 11 is a plan view of the blank from which the drawer rail of the suspension is formed.

Figures 12, 13 and 14 are end views of the parts formed from the blanks shown in Figures 9, 10 and 11, the parts being viewed from the left hand end of Figures 1 and 3.

Figure 15 is a side elevation of the modified form of suspension collapsed as it is assembled in the case. In this figure the suspension is of a much heavier construction and

is made for heavier duty than that shown in Figure 1.

55

Figure 16 is a side elevation of the suspension extended, the parts shown being the same as those shown in Figure 15, but are shown on a smaller scale.

Figure 17 is an end view, the parts being viewed from the left hand end of Figure 15.

Figure 18 is a vertical transverse section taken on the line 18^x, 18^x of Figure 16.

Figure 19 is a vertical transverse section taken on the line 19^x, 19^x of Figure 15.

65

Figure 20 is a side elevation of the intermediate parts of Figure 15, the parts being broken away or sectioned on the line 20^x, 20^x of Figure 19.

Figure 21 is a top plan view of that part of Figure 16 indicated by the arrows 21^x, 21^x.

Figure 22 is an enlarged detail view of that part of the Figure 16 indicated by the arrows 22^x, 22^x, the top flange being broken away to expose the parts that would otherwise be concealed thereby.

Figure 23 is a side elevation of the three blanks that form the stationary case channel.

Figure 24 is an end view of the case channel formed from the blanks shown in Figure 23, the parts being viewed from the left hand end of Figure 15 and as shown in Figure 17.

Figure 25 is a plan view of the blank from which the floating member of the suspension is formed.

85

Figure 26 is an end view of the floating member of the suspension formed from the blank shown in Figure 25, the part being viewed from the left hand end of Figure 15 and as shown in Figure 17.

90

Figure 27 is a plan view of the blank from which the drawer rail of the suspension is formed.

Figure 28 is an end view of this drawer rail as viewed from the left hand end of Figure 15 as shown in Figure 17.

In the several figures of the drawings, like reference numerals indicate like parts.

In the drawings reference numeral 1 indicates the plan view of the blank from which the stationary channel 1^A on the case is formed. This channel may be called the case channel. This blank is bent up so as to have a web 2 and channels 4 and 4 at the top and bottom thereof respectively. It is also provided with ears, 5, 6 and 7 by which it is suit-

ably fastened in place or interlocked with other parts, more especially the sides of the case. 8 is a slot that forms a pit in the bottom of the channel 4 into which the roller 21 of the floating suspension member 9^A settles when the drawer is closed or the parts are collapsed. 9^A is the floating suspension member that is not fastened to either the drawer or the case, but floats between them. This is shown in Figure 13 and is formed from a blank 9 shown in Figure 10. It has a web 10 at the back thereof and channels 11 and 12 at the top and bottom thereof. It is also provided with a lug 13 which extends over the drawer rail by which the drawer rail or support is held in place when it is at the outer end of its movement. It also prevents the tipping up of the file as it is withdrawn from the case.

20 The drawer rail is a Z shaped angle 14 formed from the blank 15 shown in Figure 11. It has a small flange 16 on the bottom thereof. It is also provided with a lug 17 which engages with a suitable stop on the floating member of the suspension by which the drawer support is held permanently in place on the floating suspension until it is released as will presently be described.

Neither the case channel 1^A that is stationary on the case nor the drawer rail 14 are provided with rollers. The floating suspension member is provided with four rollers as follows: It is provided with the upper rollers 18 and 19 which are of about the same diameter with each other and is provided with the lower rollers 20 and 21 which are of the same size with each other. The lower rollers have a larger diameter than the upper rollers.

40 The roller 18 is placed immediately above the roller 21 and both are located in about the middle of the slide. The roller 19 is placed at the near end of the slide at the top, and the roller 20 is placed at the forward end of the slide at the bottom. The roller 20 is 45 preferably a ball bearing roller, and the roller 21 is loosely mounted upon its axis so that it has a loose or lost motion thereon of about 3/16 of an inch permitting it to be easily fitted in place and permitting it to easily accommodate itself to the irregularities of the 50 various parts with which it comes in contact while the drawer is being moved in or out. In this sense the roller floats on its axis. As shown in Figure 5 this roller 21 sinks into 55 a slot or hole 8 in the track on which it runs when the drawer is closed. This serves to hold the drawer and floating member positively in closed position when the drawer is closed. The Z shaped member or drawer rail 60 14 is hollowed out on the under side with an inverted depression as shown in Figure 5 to receive the top of the roller 21 when the drawer is closed. This helps to keep the drawer closed. This depression registers 65 with the slot 8 and the roller 21 when the

drawer is closed so that as the drawer is pulled forward from the case, the depression in the drawer rail will serve to start the intermediate roller 21 from its seat in the slot 8 in the case channel, eliminating any drag 70 or resistance that would otherwise occur.

The forward end of the floating suspension 75 9^A is provided with a latch 22 which is pivotally mounted inside the upper channel thereof at the forward end. This latch 22 engages with the lug 17 that is formed on the drawer rail 14 and stops the forward movement of the rail and the drawer when it has reached the limit of its forward movement. The latch 22 can be swung up out of the road of 80 the lug 17 permitting the rail 14 and the drawer attached thereto to be removed from the floating suspension member and from the case.

The upper and lower channels 11 and 12 85 extend the full length of the floating suspension member except that at the rear the upper channel 11 is cut away and the web 9 extends upwardly at 23 to form a suitable bearing and back for the roller 19 as shown in 90 Figure 8. This upward extension 23 is provided with a shoulder which engages with a stationary pawl 24 when the floating member is at the limit of its forward movement, namely half way extended from the case 95 channel 1^A and its forward movement is arrested thereby.

In the blank shown in Figure 10 the latch 22 extends up through the opening 25, the roller 20 extends down through the opening 26, the roller 21 extends down through the slot 27, it being understood that when the channels 11 and 12 are formed on this blank these openings will be in the horizontal members of the channel to provide for this. It 105 will also be understood that the roller 19 extends above the floating suspension member 9^A and makes contact with the case channel, and the roller 18 is retained within the upper channel of the floating member and 110 does not extend through it and makes contact only with the drawer rail 14.

It will also be seen that the lower channel 12 at the bottom is wider than the channel 11 at the top and the rollers 20 and 21 while 115 they may be of the same thickness as the rollers 18 and 19 are spaced outwardly by small rollers placed at the back thereof.

In Figure 7^A I have shown the roller 21 mounted to turn on an eccentric 28 that is 120 mounted to swing on a pivot so that the roller will accommodate itself to any irregularities in the channel on which it rests. In Figure 7^B I have shown the roller 21 mounted to turn on a pivot that is mounted on the 125 swinging link 29.

In Figure 23 I have shown the members that go to make up the case channel for a heavier construction of a roller suspension of this same invention. In this figure the

blank 41 is bent to form the Z shaped angle or drawer rail 42. The blank 43 is bent to form the angle 44 and the blank 45 is bent to form the Z shaped angle 46. The angles 42, 44 and 46 are fastened directly to the inside of the case which holds the drawers and the side of the case is therefore a part of the channel that is formed by these three angles. It will be understood that the Z shaped angle 46 is a reinforce for the forward part of the angle 44 and is used to strengthen it over what it would be if formed from sheet metal of ordinary thickness. The Z shaped angle 46 carries the flange that completes the channel. This flange extends for about half the length of the angle 44 namely the forward half of the length, it being understood that it is not necessary to provide a flange at the rear end of the angle 46 for the roller 51 of the floating member does not go back that far and the floating member is sufficiently guided at the rear by the lower flange on the Z shaped angle 42 which runs the whole length thereof and overhangs and guides the floating member from above.

The blank 47 shown in Figure 25 is formed into the channel 48 as shown in Figure 26, this being the floating member. The lower groove of the channel is made wider than the upper groove of the channel for the reason that the lower rollers 51 and 52 that are carried by the floating channel are thicker or wider than the upper rollers 53 and 54 carried at the top of the floating channel, and are spaced out by collars placed at the back thereof. The slots or recesses 49 and 50 are provided in the bottom groove so that the rollers 51 and 52 can extend therethrough to make contact with the bottom of the groove formed by the angles 44 and 46.

The rollers 53 and 54 are carried at the top of the floating channel, the roller 53 being located above the roller 51 both being located in the middle of the channel, the roller 54 being located at the rear end of the channel and the roller 52 being located at the forward end of the channel.

The blank 55 shown in Figure 27 is bent into the Z shaped angle 55^A shown in Figure 28. This angle is attached to the drawer and is stationary therewith and is called the drawer rail. The horizontal part of the angle 56 is reinforced by the plate 57 to take the wear and strain that would otherwise have to be taken by the thin horizontal member. As shown in Fig. 28, the Z shaped angle is bent up of sheet metal and is reinforced by the plate 57 but it may be rolled all in one piece, the horizontal member being made thicker than the vertical member to give the strength and wearing qualities where it is most needed.

In the floating suspension member the roller 54 is mounted on a pivot one end of which is fastened in the web of the channel

and the outer end of which is supported by the Z shaped bracket 58 that is fastened to the web of the channel. Over the roller 53 is placed the bracket 59 both ends of which are fastened to the web of the channel of the floating suspension member. At the forward end of the floating suspension member is carried a sliding latch 60 which has a slot 61 therein which engages with the pin 62 on which the latch swings. This latch engages with a block 63 on the Z shaped member 55^A as shown in Figure 21 by which the movement of the drawer is arrested when the suspension has been fully extended. By lifting the latch at its outer end, the block 63 can pass under the latch, and the drawer can be removed from the suspension.

The roller 51 is loosely mounted upon the pivot 64 so that it can float up and down as shown in Figure 20. It extends through a slot in the bottom of the channel so that it can rest on the angle 44 that is fastened to the case, and on which it rolls as the floating member moves back and forth. This angle is cut away at 65 immediately under where the roller 51 rests when the drawer is closed so as to form a depression in which the roller will rest and by which the roller and its suspension and drawer will be normally held in place with the drawer closed. When the drawer is opened, the roller will be lifted out of this stationary depression or slot by the moving depression in the drawer rail.

The rollers 52, 53 and 54 can be either roller bearings or turned rollers, but the roller 51 is always made solid.

The intermediate floating member is made so that it can be removed from the channel on the casing by tilting the upper part of it sideways when the drawer is out. This is because when the Z shaped bar attached to the drawer is not in place over the rollers 21 or 51 the floating member can drop down on the roller 21 or 51 so as to disengage the rollers at the top from the overhanging flange of the channel. When the Z shaped bar is in place, the floating member is held up because of the engagement of one or both of the upper rollers therewith and because it in turn engages the rollers 21 or 51. Then too, the floating member is held in place by the drawer itself which holds the Z shaped member in place.

The floating member 48 is provided with the lug 67 which engages over the drawer rail 55^A and holds it from tilting as the lug 13 engages over the rail 14 as above described.

The case channel is provided with the block 68 which engages the roller 54 on the floating channel and limits the forward movement thereof when the drawer is fully extended.

I claim:

1. In a progressive roller suspension, the combination of a stationayr channel fastened to the case, a Z shaped rail fastened to the drawer and a floating channel interposed be-

tween the two, said floating channel having two rollers pivotally mounted at the middle thereof one above the other, the lower roller having its pivot near the bottom of the channel, a slot in the bottom of said channel through which the lower roller extends to make contact with the bottom of the case channel, said floating channel having a roller at the upper rear corner which makes contact with the top of the case channel and a roller at the lower front corner which supports the drawer rail, a slot in the case channel centrally thereof adapted to receive said lower roller when the drawer is closed.

5 10 15 20 25 30 35

6 2. In a progressive roller suspension, the combination of a case channel, a floating channel moving therein, said suspension having 4

rollers therein, two of said rollers being in the middle of the floating channel one above the other, a third roller being on the lower side 20 of the floating channel at the forward end thereof, a Z shaped rail fastened to the drawer having a horizontal member and a lower flange on one side thereof and an upper flange 25 on the other side thereof, the horizontal member of said rail engaging between the two rollers at the middle of the suspension resting on said two lower rollers of the floating channel and the lower flange of said rail engaging behind said two lower rollers, the upper flange 30 engaging the drawer.

In testimony whereof I affix my signature.

JAMES RICHARD JONES.
